UNITED STATES PATENT OFFICE.

HANNAH C. FRASER AND MARY ANN FRASER, OF BOURNEMOUTH, ENGLAND.

HAIRPIN CUSHION.

Application filed October 12, 1923. Serial No. 668,135.

This invention has reference to hair pin cushions, its object being to provide a hair pin cushion which is particularly adapted to be used for gripping and supporting hair pins and the like and for retaining them in any desired position and in readiness for easy removal.

In accordance with the present invention, the hair pin cushion consists of an inner portion of easy penetrable loose stuffing and one or more covers formed as a net or the like, which wholly, or partly, encloses the said stuffing.

Preferably, horse hair is used as the stuffing of the cushion but any other loose stuffing of a fibrous nature may be used, which permits the easy entry of a blunt pointed instrument such as a hair pin, or the like, and yet grips the said hair pin or the like after its entry into the cushion. The whole or part only of the centre stuffing may, as aforesaid, be enclosed by a cover, which latter may take the form of a fine wire, hair or silk net or a net made of hair net having an open mesh. The term "net" is also intended to include loosely woven fabric through which a blunt pointed instrument can be inserted.

It will be readily understood that the present invention may be applied to many and varied constructional forms of a cushion for hair pins, and the like, and the annexed drawing illustrates, by way of example, a few of the said constructional forms.

On the drawing:—

Fig. 1 illustrates the application of a cushion to a china figure.

Fig. 2 shows a cushion mounted in a stand.

Fig. 3 is a view of a large cushion secured to the body of a doll and a smaller cushion forming the doll's hat.

Fig. 4 illustrates a form of cushion in which the edges of the net are secured to a length of elastic.

Fig. 5 is a fragmentary view of a cushion comprising a cover formed of two nets.

Referring to the drawing:—

Each cushion A illustrated in Figs. 1 to 4 comprises a cover B and a loose stuffing C, of horsehair, enclosed by the said cover. The latter is, in the case of each of the constructional examples, made in the form of a net of dyed silk, having an open mesh, through which hair pins and the like may be

inserted, as clearly shown in Fig. 1. The horsehair stuffing is before use, thoroughly cleansed and dyed to the desired shade and is then teased so as to form a loose mass which permits the easy entry of a hairpin or the like.

In Fig. 3, the doll is shown provided with a hat forming a cushion which is, by reason of its thickness allowing the ends of the pins to project well out of the outer cover 65 with no danger of said pins being lost in the cushion, particularly adapted to be used for holding ordinary pins, whilst the lower cushion can be used for holding larger pins such as hair pins. 70

A cushion A mounted as illustrated in Fig. 2 provides a very pleasing ornament for a lady's toilet table. The cushion is accommodated partially within and partially without a silver stand D comprising a lattice E 75 and having legs F.

In constructing cushions for application to figures such as those illustrated in Figs. 1 and 3, the stuffing C is enclosed by the net B, as previously described, but the edge 80 of the said net is preferably secured to a length of elastic G, as shown in Fig. 4. This method of securing the ends of the net makes it possible to apply a cushion to an article of any design, without the necessity 85 of a great deal of tedious work in securing the net to the article itself. Either one or two lengths of elastic may be used, that is to say, the cushion may be fixed on the article by the gripping action of the band 90 of elastic at the top only of a cushion or at the top and bottom thereof as shown at G¹ and G² in Fig. 3. When elastic bands are used it is not necessary to draw the free ends of the net tightly together, less stuffing is 95 required and it is possible to form the cushion into any desired shape.

Referring now to Fig. 5; it will be seen that the outer cover B comprises an outer and somewhat coarse silk net H and an inner 100 fine silk net J which enclose a loose horse hair stuffing, the free ends of both nets being secured to a length of elastic (not shown).

Although in the constructional forms of 105 our invention, hereinbefore described, we have referred to the use of silk nets to form an outer cover, there are many other suitable materials that we may use for this purpose such, for example, as fine wires, human hair, 110

hair net and loosely woven fabric. Moreover, the horse hair forming the inner stuffing may be replaced by a stuffing of hair padding, tow, teased rope, fibre, bristles, 5 cocoanut fibre or wool. Shavings of suitable materials may also be used, either alone or in combination with horse hair or with one of the substitutes therefor.

The use of constructional forms of our 10 invention is not restricted to holding hairpins alone, as hat pins, fancy hair combs, pins, needles and the like may be held by the said constructional forms, but in the case 15 of pins and needles the cushion should be made sufficiently shallow to prevent the loss 20 of the pins or needles within the stuffing.

Many additional forms of the hair pin 25 cushion may be provided, as for example, a nest, bracket, or a hanging pad, or we may 30 combine any suitable constructional form with another toilet article such as a hair tidy, pin cushion, or the like. The cushion may also be secured to the top of a small stand 35 or stool and is particularly adapted to be used for displaying hairpins, hat pins, and fancy hair combs and the like for sale and 40 may be constructed in any form suitable for this purpose, and weighted at its bottom, if desired.

Having now fully described our invention 45

what we claim and desire to secure by Letters Patent is:—

1. A hair pin cushion, comprising a body portion formed of loose resilient fibrous material, a wide mesh flexible net surrounding the body portion, the top and bottom edges of the net being gathered and secured in such gathered relation to hold the net 55 around the body portion.

2. A hair pin cushion, comprising a body 60 portion formed of loose resilient fibrous material, a net surrounding the body portion, and an outer net of wide mesh surrounding the body portion, the top and bottom edges of the outer net being gathered 65 and secured to hold the said outer net around the inner net and body portion.

3. A hair pin cushion, comprising a body 70 portion formed of loose resilient fibrous material, a wide open mesh net surrounding the body portion, and an elastic securing means to cause the ends of the net to be gathered and drawn in around the body portion to thereby define an opening at such 75 gathered portion which may be resiliently extended.

In testimony whereof we affix our signatures.

HANNAH C. FRASER.
MARY ANN FRASER.
